UNITED STATES PATENT OFFICE.

JOHN O. NEIKIRK, OF CHICAGO, ILLINOIS, ASSIGNOR TO NATIONAL DUMP CAR COMPANY, OF CHICAGO, ILLINOIS, A CORPORATION OF MAINE.

CENTER SILL.

1,129,416.

Specification of Letters Patent. Patented Feb. 23, 1915.

Application filed April 1, 1910. Serial No. 552,849.

To all whom it may concern:

Be it known that I, JOHN O. NEIKIRK, a citizen of the United States, and resident of Chicago, in the county of Cook and State 5 of Illinois, have invented a certain new and useful Improvement in Center Sills, of which the following is a description, reference being had to the accompanying drawing, which forms a part of my invention.

10 My invention relates to metallic center sills of the underframe of steel cars, and has for its object the provision of a center sill that is adapted to withstand the various strains to which the underframing of a rail- 15 way car is subject; the improved sill being especially intended to withstand the longitudinal or twisting strains encountered through the collisions or bumps of the car- 20 ends, either in a direction parallel with or at an angle to the longitudinal axis of the sill, as will more fully appear from the following specification.

25 In the drawing:—Figure 1 is a plan view of a portion of a car underframe, with my improved sill. Fig. 2 is a cross sectional view taken on lines 2—2 of Fig. 1. Fig. 3 is a similar sectional view taken on line 3—3 of Fig. 1. Fig. 4 is a perspective view of a portion of my improved center sill. Fig. 5 is a cross-sectional view similar to Fig. 3, 30 but showing a modified form.

35 The invention is shown applied to the steel underframe of a car; the center sill A, in Fig. 1, extending from one end sill B, to the other and being suitably connected with the cross members C and also the gusset- plates D.

40 The center sill A, as illustrated in the drawing, comprises a vertical web a, which extends from one end sill to the other and is of equal dimensions throughout its length. The upper edge of the center sill is provided with horizontally extending flanges, which consist of angle irons b. These angle 45 irons b are preferably of the same dimensions throughout their length, extending from end to end of web a, and may be secured to the central web a, as well as to each other, by a single set of rivets; the 50 rivets passing through both of the angle irons and the web as shown in the cross sectional views. The lower edge of the sill is also provided with horizontally extending flanges, the edges of which are preferably 55 turned at right angles or in a vertical direc-

tion to the center or web portion of the flange, thereby constituting what are known as Z-bars c. These Z-bars c, are also shown secured to opposite sides of the web a, and to each other, by a single set of rivets which 60 pass through all three of the members as shown in Figs. 2 and 3. The horizontally disposed web portion of these flanges or Z-bars c are shown bowed or bellied at the center or at a point intermediate of its ends; 65 or made to taper from the center toward the ends of the sills A; the web of the bars c being of substantially the same width—horizontally—intermediate of a point near the bolsters, as for example, near the line 70 2—2 of Fig. 1 and the end sills. The extent to which the lower flange is bowed or bellied horizontally is clearly shown in Figs. 1, 2, and 3.

75 It is apparent from this construction that the sill is capable of withstanding great strains, the horizontally disposed bellied or tapering portion extending throughout the greater part of the sill intermediate of its ends where it would be more likely to buckle 80 or twist through any impact that the ends might encounter; the construction thus practically forming a longitudinally extending column wider at its intermediate points than at its ends and adapted to withstand any 85 strains to which the underframe of the car might be subjected, regardless of the direction of the impact.

90 The center sill need not necessarily be constructed in every respect as just described, and I do not wish to be understood as limiting myself to the exact construction herein- 95 before set forth, as the same may be varied without departing from the spirit of my invention; for example, in Fig. 5 I have shown a modified construction wherein the lower flange is made of the channel irons c', which are preferably inverted as shown. These channel irons c', like the Z bars c, are se- 100 cured to the opposite sides of the vertical web a and also to each other by a single set of rivets or other suitable means of fastening. These channel irons c', like the Z bars c, are also bellied or bowed intermediate of the ends in a similar manner, and are capable 105 of withstanding any strains to which they might be subjected and which would buckle or twist the ordinarily constructed center sill.

110 By constructing the horizontal flanges,

either in the shape of Z bars or channel irons; that is, with the edges of the flanges at an angle to the web portion thereof or extending vertically, it is evident that the 5 horizontally extending portions of the sill are greatly strengthened against any tendency to twist or buckle; thus reinforcing or adding to the increased strength obtained by a bellied or tapered horizontally-extending flange as herein set forth.

Having thus described my invention, what I wish to secure by Letters Patent, is:—

1. A center sill, composed of a number of members, the one constituting the web portion while the others constitute horizontally disposed flange portions at the lower edge of the web portion, the web member and flange members being composed of continuous portions throughout the center sill, with 15 the two flange members gradually tapering toward the ends of the sill.
2. A center sill, comprising a vertical web

and horizontally disposed flanges at the lower edges of said web, the web and flanges being composed of separate continuous portions throughout the length of the center sill, the flanges being made tapering toward the ends of the sill, with the edges of the flanges provided with reinforcing portions.

3. A center sill, comprising a vertical web and horizontally disposed flanges at the edges of said web, the web and flanges being composed of separate continuous portions throughout the length of the center sill, the flanges at the lower edges of the web tapering toward the ends of the sill, with the outer edges of the flanges at the lower edges of the web provided with vertically disposed edges.

JOHN O. NEIKIRK.
